W. A. FRICKE

PHONOGRAPH MECHANISM

Filed May 12, 1923

UNITED STATES PATENT OFFICE.

WILLIAM A. FRICKE, OF OAK PARK, ILLINOIS.

PHONOGRAPH MECHANISM.

Application filed May 12, 1923. Serial No. 638,524.

To all whom it may concern:

Be it known that I, WILLIAM A. FRICKE, citizen of the United States, residing at Oak Park, in the county of Cook and State 5 of Illinois, have invented a certain new and useful Improvement in Phonograph Mechanism, of which the following is a full, clear, concise, and exact description.

My invention relates to phonographs employing electric motors for driving the revoluble record supports thereof, my invention having for its object the provision of adjusting means whereby the duration of the closure of a switch in the motor circuit 15 may be regulated to suit the lengths of records being played.

In accordance with my invention I employ a member in actuating relation to the switch to open and close it and a gearing 20 driven by said motor and driving said member and with respect to which said member is adjustable to adjust the duration of the closure of the switch.

In the preferred embodiment of the invention the controlling member is in the form of a cam and there is an intermediary pivoted lever having one end engaged by the cam and the other end in actuating relation to the switch. This cam is coupled 30 with an element of the gearing by means of a friction coupler which permits adjustment of the cam with respect to an element of the gearing whereby the duration of the closure of the switch and the duration of 35 the playing of the record may be regulated.

I will explain my invention more fully by reference to the accompanying drawing showing the preferred embodiment thereof and in which Fig. 1 is a sectional view 40 on line 1—1 of Fig. 2; Fig. 2 is a sectional view on line 2—2 of Fig. 1; Fig. 3 is a sectional view on line 3—3 of Fig. 1; and Fig. 4 is a plan view of an indicating scale 45 which may be employed as an aid to the adjustment of the switch controlling cam or member.

Like parts are indicated by similar characters of reference throughout the different 50 figures.

The revoluble record support illustrated 55 is in the form of a turn table 1, though the invention is not to be thus limited. A shaft 2 of the turn table is coupled with an electric motor 3, diagrammatically illustrated, by means of speed reducing gear-

ing, also diagrammatically indicated, and of which an element 4 is upon the shaft. A switch having complementary contact springs 5 and 6 is included in series with the motor and the generator 7. When this 60 switch is closed the motor is set into action and when it is opened the motor is brought to rest by the retarding action of said gearing. The switch is placed in a closed position by means of an intermediately pivoted lever 8, one end of which is engageable with the longer contact spring 6 to elevate this spring into engagement with its complement 5 to close the motor circuit. When this lever is placed in an alternative 70 position the end thereof that is engageable with the spring 6 is removed from beneath this spring to permit this spring to separate from the spring 5, the resilience of the 75 spring 6 being sufficient for this purpose.

The lever 8 is controlled by gearing which is driven by the motor 3. For the sake of convenience, this gearing is driven from the turn table shaft 2. I have illustrated a gear element 9 upon the hub 10 of 80 the turn table and a worm pinion 11 in mesh with the gear 9. This worm pinion is upon one end of a shaft 12. A worm 13 is formed in the other end of this shaft and is in mesh with a worm wheel 14. A cam 15 is keyed to a shaft 16 which passes centrally through the worm gear 14. A friction coupler, preferably in the form of a friction washer 17, made of cork, is interposed between the cam 15 and the worm 90 gear 14. The nut 18, threaded upon the lower end of the shaft 16, serves to press the spring washer 19 against the worm gear 14 with sufficient pressure to enable the friction washer 17 to have holding engagement with both the cam 15 and the wheel 14 whereby the wheel 14 will serve to drive the shaft 16. As illustrated, there is an antifriction washer 20 above the cam 15 and engageable with the framework 21 to 100 eliminate any direct frictional engagement between the cam and said frame work, the washer 20 being preferably of fibre.

A knurled head 22 is fixed upon the upper end of the shaft 16 whereby said shaft 105 and the cam 15 coupled therewith may be turned a selected distance, the spring washer 19 and the friction washer 17 permitting this movement of the cam with respect to the gear element 14 which is pre- 110

vented from accompanying the cam in its adjusting movement by reason of the engaging teeth of the wheel 14 and worm 13.

The cam has a circular dwell 15', concentric with the shaft 16, which engages the end of the lever 8 opposite the lever end that is engageable with the switch spring 6, this dwell of the cam maintaining the lever 8 in the position in which the switch 5, 6 is closed. As illustrated, the end of the lever which engages the cam is formed with a finger 23 which projects upwardly into the plane of the cam, this finger being maintained in engagement with the cam by means of a spring 24 that engages the switch end of the lever 8 and which spring exerts pressure upon the lever 8 in a direction that tends to remove the lever from beneath the switch to permit the switch to open. The cam rotates in a clockwise direction, the duration of the switch closure depending upon the portion of the cam 15 that engages the lever finger 23. The cam is adjustable with respect to the element 14 to regulate the portion of the cam dwell that is engageable with the lever finger to regulate the duration of closure of the switch and thereby the duration of the playing of the record.

In the embodiment of the invention illustrated a pointer 26 is in fixed assembly with the shaft head 22. There is a scale 27 concentric with the shaft 16 and suitably marked to enable the user to determine the number of revolutions which the motor switch will permit the motor to turn the record support. The beginning of this scale is marked with the word "Start" and the end thereof is marked with the word "Stop," these ends of the scale being spaced apart to correspond to the space between the cam drop 25 and the leading end 15² of the cam dwell 15'. Another scale 28, concentric with the scale 27 and the shaft 16, is marked in an opposite direction from the scale 27. The scale 28 may be employed to measure the number of revolutions required to play a record, the record being marked with such number, the pointer 26 being placed at this number upon the scale 27 in playing the record.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. The combination with the revoluble record support of a phonograph; of an electric motor in driving relation to said support; a switch in circuit with the motor for bringing it into and out of action; a cam in

actuating relation to the switch to open and close it and having one portion that serves to maintain the switch closed and another portion which causes the switch to open; and gearing driven by said motor and driving said cam and with respect to which said cam is adjustable to adjust the duration of the closure of the switch.

2. The combination with the revoluble record support of a phonograph; of an electric motor in driving relation to said support; a switch in circuit with the motor for bringing it into and out of action; a cam in actuating relation to the switch to open and close it and having one portion that serves to maintain the switch closed and another portion which causes the switch to open; gearing driven by said motor and driving said cam; and a friction coupler for coupling said cam and an element of said gearing to permit adjustment of said cam with respect to said gear element to adjust the duration of the closure of the switch.

3. The combination with the revoluble record support of a phonograph; of an electric motor in driving relation to said support; a switch in circuit with the motor for bringing it into and out of action; an intermediately pivoted lever engageable at one end with said switch to place the switch in either of its alternative positions; a member engageable with the other end of said lever to open and close the switch; and gearing driven by said motor and driving said member and with respect to which said member is adjustable to adjust the duration of the closure of the switch.

4. The combination with the revoluble record support of a phonograph; of an electric motor in driving relation to said support; a switch in circuit with the motor for bringing it into and out of action; an intermediately pivoted lever engageable at one end with said switch to place the switch in either of its alternative positions; a cam engageable with the other end of said lever to open the switch and having one portion that serves to maintain the switch closed and another portion which causes the switch to open; and gearing driven by said motor and driving said cam and with respect to which said cam is adjustable to adjust the duration of the closure of the switch.

5. The combination with the revoluble record support of a phonograph; of an electric motor in driving relation to said support; a switch in circuit with the motor for bringing it into and out of action; an intermediately pivoted lever engageable at one end with said switch to place the switch in either of its alternative positions; a member engageable with the other end of said lever to open and close the switch; gearing driven by said motor and driving said member; and a friction coupler for coupling said

member and an element of said gearing to permit adjustment of said member with respect to said gear element to adjust the duration of the closure of the switch.

- 5 6. The combination with the revoluble record support of a phonograph; of an electric motor in driving relation to said support; a switch in circuit with the motor for bringing it into and out of action; an intermediate pivoted lever engageable at one end with said switch to place the switch in either of its alternative positions; a cam engageable with the other end of said lever to

open the switch and having one portion that serves to maintain the switch closed and another portion which causes the switch to open; gearing driven by said motor and driving said cam; and a friction coupler for coupling said cam and an element of said gearing to permit adjustment of said cam with respect to said gear element to adjust the duration of the closure of the switch. 15 20

In witness whereof, I hereunto subscribe my name this 25th day of January, A. D. 1923.

WILLIAM A. FRICKE.
